UNITED STATES PATENT OFFICE

JOHN M. POWERS, OF VALLEY FALLS, NEW YORK

RAIL CHAIR

Application filed June 18, 1929. Serial No. 371,843.

This invention relates to an improved railway tie plate or chair, and it has reference to an improvement in the general construction of said reinforcing chairs, whereby to permit the rails to be seated and fastened thereto.

In carrying out the invention it is my aim to generally improve upon structures of this class by providing a novel arrangement of features and details which cooperate in a manner to produce a more efficient rail chair construction, one which is economical, susceptible of rapid installation and removal, and otherwise efficient in fulfilling the requirements of a structure of this class in a highly satisfactory and dependable manner.

Another object of the invention is to provide novel metallic channel shaped chairs or bed plates made in left and right types to permit "throwing in" to compensate for adjustment as the rails wear.

Other features and advantages of the invention will become more readily apparent from the following description and drawings.

In the drawings:

25 Figure 1 is a fragmentary elevational view showing the opposite end portions of the wooden tie with the metallic chairs fastened thereto and the rails fastened thereon.

30 Figure 2 is a top plan view of the structure seen in Figure 1.

35 Figure 3 is a view like Figure 1 with portions broken away and shown in section, and further showing the cooperation of features and the shifted or adjusted position of one of the rails.

Figure 4 is a fragmentary top plan view of one of the chairs with the rail removed.

40 Figure 5 is a perspective view of the complementary chair, and

Figure 6 is a perspective view of the chair shown in Figure 3 by itself.

In the drawings in Figure 6 the reference character 7 designates a chair or bed plate, which is adapted to be fastened on the wooden tie 8. This plate is of general U-shaped configuration and includes a central web portion 9 which forms the bed for the base flange of the complementary rail 10. The chair 7 is provided with down turned reinforcing and anchoring flanges 11 provided with alined

holes to accommodate the fastening bolts 12 and 13. These bolts extend transversely through the tie at about the center and in the same horizontal plane. The bolts are of course in spaced parallelism. In accordance 55 with this particular species of chair, it is provided on one side with an upstanding or elevated portion constituting a shoulder 14. In addition it is provided with staggered holes 15 and 16 to accommodate spikes 17 and 18. 60 The tie is notched out adjacent one end as at 19 to permit the portions 9 and 14 to fit therein to dispose this portion of the chair substantially flush with the tie top.

The complementary rail is designated by the 65 reference character 20 and this cooperates with the chair 21. This is of the same configuration as the chair shown in Figure 5, and it includes the central web portion 22 on the opposite sides of which are spaced parallel elevations forming shoulders 23 and 24, producing a channel in which the base flange of the rail 20 is seated. Here again I provide holes 25 and 26 for the spikes 27 and 28. In addition the attaching flanges 29 are provided, and these are fastened to the tie by the cross bolts 30 and 31. The tie has its end portion notched to permit the web portion of the chair to be seated flush therein. 70

Particularly do I wish to emphasize the 80 reinforcing flanges for the wooden tie and the bolts for fastening the metallic chairs in place. Then too I call attention to the fact that the openings 15 and 16 of the left hand chair 7 are enlarged somewhat. This is to allow for the so called "throwing in" of the rail at predetermined intervals. After the rail is worn a certain distance it is customary to shift the rail over, that is, in a direction from left to right in Figure 3. Normally it occupies the position seen in Figure 1, and after the wear takes place it is moved over slightly to the position seen in Figure 3. This necessitates withdrawal of the spikes 17 and 18, and placement of wedge plugs 32 85 therein. These plugs constitute fillers and aid in retaining spikes in place as they are again driven in place. There being no shoulder at the right on the chair 7 it is obvious that the rail can be shifted over at least a 100

half inch which is the reason for the elongated formation or enlarged holes 15 and 16.

- It is obvious that the spike holes are such as to permit regular spikes to be used in anchoring the rail chairs to the tie and the rail to the chairs. When the rail is thrown in a half inch or so, the track men will insert one of their regular tie plugs (a wooden plug the same size as the steel spikes) and this will effectively fill the hole where the spike is removed. Then it will be necessary only to insert the spike in a new place after the rail is thrown in. The bolts of course will not be disturbed at any time during the life of said tie, the only difference in the position of the bolts is that the bolts on the side where the rail is to be shifted will have to be one half inch nearer together than on the other end or side to allow for the adjustment.
- A careful consideration of the description in connection with the drawings will enable persons skilled in the art to which the invention relates to obtain a clear understanding of the construction, method of assembly, handling, adjustment, etc. Therefore, a more lengthy description is believed to be unnecessary.

Minor changes in shape, size, materials, and rearrangement of details coming within the field of invention claimed may be resorted to in actual practice if desired.

Having thus described the invention what I claim as new and desire to secure by Letters Patent is:—

- A rail chair of the character described comprising a web portion having transversely extending slots adjacent its longitudinal marginal sides for the passage of anchoring spikes, said web portion being further provided, on its upper face, with a longitudinally extending raised marginal portion providing a rail engaging shoulder intersecting the respective slot, all of the slots being of a size to permit the spikes to be shifted therein to permit the rail to be shifted laterally and secured in shifted position on the web portion.

In testimony whereof I affix my signature.
JOHN M. POWERS.
